WIND FLY SCARER

Filed March 7, 1927

FIG. 2

FIG. 1

FIG. 4

FIG. 3

FIG. 5

INVENTOR
Frederick E. Sharp
BY *E. Sharp*
ATTORNEY

UNITED STATES PATENT OFFICE.

FREDERICK E. SHARP, OF FRESCOTT, WASHINGTON.

WIND FLY SCARER.

Application filed March 7, 1927. Serial No. 173,294.

This invention relates to wind fly scarers and has as one of its objects to provide a fly scarer that will drive flies from a closure upon opening that member.

Another object of the invention is to provide a fly scarer that may be attached readily and which is highly efficient in operation.

A further object of this invention is to provide a fly scarer that is adaptable to right or left hand opening closures.

With these and other objects in view reference is now had to the accompanying drawings in which

Fig. 1 is a perspective view of a closure and frame showing the device attached;

Fig. 2 is a sectional side elevation of a fragment of the device;

Fig. 3 is a plan view of the operating lever;

Fig. 4 is a side elevation thereof; and

Fig. 5 is a plan view from below of the bellows showing method of reversing the operating lever.

Having reference to the drawings like numerals refer to like parts throughout the several views, and the numeral 1 refers to a closure which may be of the screen door variety, or similar door, opening on hinges 2 supporting the door from a frame 3 consisting of side pieces 4 and the top piece 5.

Let it here be understood that while reference is being made throughout the specifications to the frame as a means of support for the device, it is obvious that it may be attached to a side wall as well.

The device consists of a wind supplying means 6 comprising preferably a bellows 7 having the usual upper plate 8 and lower plate 9, the upper plate being stationary in this case and attached to the frame by brackets 10, and the lower plate being movably attached at the inner end to the upper plate 8 by the usual flexible connection 11. The lower plate is provided with nozzles 12 that are directed towards the closure, and these nozzles, by the movement of the lower plate during operation will change the direction of a blast of wind therethrough so that it will follow the closure in its movement of opening or closing, and a valve 13 is provided to admit air to the bellows as it is expanded.

A weight 14 may be confined within the bellows or attached thereto to maintain the bellows in the expanded position, it is obvious however that a spring (not shown)

may be interposed between the top and bottom plates, in the usual manner of such construction, for the same purpose.

During operation the lower plate has a general up and down movement and ribbons 15 may be attached to the edge of the lower plate, to be agitated by the deflected current of wind striking the ribbons during the movement of this member.

To operate the bellows a reversible operating lever 16 is provided which in plan is of a generally circular form, with tangentially positioned ends 17 adapted for engagement by clips 18 secured to either end 65 of the lower plate 9 of the bellows.

By this form of lever the lever may be attached at either end of the bellows to register with the closure constantly during its movement in opening and closing, and 75 whether the closure is hung to operate from the left hand or right hand side of the frame.

The reversible lever is provided with depressions 19 and 20, of equal distance from 80 the ends of the tangent, and of equal form, with a central raise 21.

Attached to the upper part of the closure a roller 22 is provided for engagement with the operating lever and it is obvious that 85 during the movement of the closure the roller will contact the lever providing for a gradually increased contraction of the bellows and an alternating expansion as the roller encounters the depressions 19 and 20, 90 with a maximum contraction obtaining as the roller engages what might be termed the high point 21 of the lever.

From this description it is obvious that an alternate up and down movement of the 95 bellows will obtain during the movement of the closure in either direction of opening or closing, and by this means the wind is forced against the door in gusts, the ribbon is agitated by this movement of the lower 100 plate, and with the wind following the door as the lower plate raises and the door is moving the combination will be highly effective for the purpose for which it is intended.

In operation the brackets 10 are secured 105 to the frame, the bellows 7 is attached to the brackets or suitable support thereby, and the reversible operating lever is attached to the respective clip 18 that is above the hinged side of the closure.

The roller 22 is then attached to the closure and with this assembly upon the move-

ment of the closure any flies or other insects lodged thereon will be frightened by the ribbon and dislodged by the wind, until the door has had opportunity to resume its closed position.

While the device is an efficient fly scarer it is obvious that it may be arranged as to surface dimensions of the top plate to admit of being utilized as a shade or awning over the closure.

Having thus described my invention, I claim:

1. In a wind fly scarer, a closure, a bellows attached adjacent to said closure, and means adapted to operate said bellows with the movement of said closure.

2. In a wind fly scarer, a closure, a bellows attached adjacent to said closure, and a reversible operating lever adapted to operate said bellows with the movement of said closure.

3. In a wind fly scarer, a closure, a bellows attached to the frame of said closure, and a reversible operating lever attached to said bellows and adapted to register constantly with the closure during the movement of that member.

4. In a fly scarer, a closure, a roller bearing attached to said closure, a bellows attached to the frame of said closure, ribbons attached to said bellows and positioned for agitation by the wind therefrom, and a reversible operating lever attached to said bellows in register with said roller bearing, said lever being formed to provide an alternating expansion and contraction of said bellows during the movement of the closure in either direction.

In testimony whereof I have affixed my signature.

FREDERICK E. SHARP.
